UNITED STATES PATENT OFFICE.

MORRIS LEVITAN, OF NEW YORK, N. Y.

DESIGN FOR AN ELECTRIC-LIGHTING CEILING FIXTURE.

Application filed August 12, 1926. Serial No. 18,702. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for an Electric-Lighting Ceiling Fixture, of which the following is a specification, reference being had to the accompanying drawing, forming a part thereof.

Figure 1 shows a side view of my new electric lighting ceiling fixture, showing my new and ornamental design. It is to be

noted that only a portion of the surface ornamentation is shown, the unornamented parts involving a mere repetition of the completed portions.

Figure 2 is a diagrammatic bottom plan view of my electric lighting ceiling fixture for the purpose of showing contour thereof, the ornamentation being omitted.

I claim:

The ornamental design for an electric lighting ceiling fixture, as shown.

MORRIS LEVITAN.
